CYCLE DIFFERENTIAL AXLE

Lynda H. Garrison, 305 N. Orchid,
Ellenton, Fla. 33532

Filed May 22, 1975, Ser. No. 579,853

Term of patent 14 years

Int. Cl. D12—11

U.S. Cl. D12—114

FIG. 1 is a top plan view of a cycle differential axle showing my new design, the bottom being a mirror image thereof; and

FIG. 2 is an end elevational view of FIG. 1, the opposite end being a mirror image thereof.

I claim:

The ornamental design for a cycle differential axle, as shown.
